UNITED STATES PATENT OFFICE.

MATHEW E. ROTHBERG, OF PITTSBURG, PENNSYLVANIA, ASSIGNOR TO THE COAL AND COKE BY-PRODUCTS COMPANY, A CORPORATION OF WEST VIRGINIA.

COKE-OVEN.

No. 893,017.

Specification of Letters Patent. Patented July 14, 1908.

Application filed January 13, 1908. Serial No. 410,477.

To all whom it may concern:

Be it known that I, MATHEW E. ROTHBERG, a citizen of the United States, and a resident of Pittsburgh, in the county of Allegheny and State of Pennsylvania, have made certain new and useful Improvements in Coke-Ovens, of which the following is a specification, accompanied by illustrative drawings.

- 10 The invention relates particularly to the flues by which the ovens are heated, and its object is to improve the combustion in the flues and give a more uniform heat to the oven.
- 15 The invention is particularly applicable as an improvement of the ovens shown in United States Letters Patent No. 841,052, of January 8th, 1907, to Rothberg and Ernst, but it is by no means restricted to such application, as will be evident.

The accompanying drawings illustrate the invention in its preferred form only.

Figure 1 is a vertical section through an oven wall on the section line 1—1 of Fig. 5. Fig. 2 is a partial cross section on the line 2—2 of Fig. 1. Figs. 3 and 4 are similar sections on the lines 3—3 and 4—4. Fig. 5 is a partial horizontal section on the line 5—5 (Fig. 1). Fig. 6 is a similar section on the line 6—6 (Fig. 1). Fig. 7 is a partial longitudinal section through battery ovens on the line 7—7 of Fig. 8, partly diagrammatic and omitting some of the parts not directly concerned. Fig. 8 is a horizontal section on the line 8—8 (Fig. 1).

In the preferred form of the invention illustrated, some of the coking chambers are marked 9 and the heating flues are arranged in the side walls in each of these chambers. It will be understood that preferably the gas from the oven is carried off through suitable pipes and some of it is utilized to produce combustion and heat the ovens. The invention primarily concerns the manner in which the gas and air are introduced and burned in the flues and the hot waste gas so produced carried off. The hot waste gases from the heating flues are carried down to the waste gas main 10. These gases are then drawn back through one of the regenerating chambers 11, highly heating the same, and thence to the stack 12. The other regenerating chamber is used to heat the incoming fresh air which enters from the atmosphere

into the passages 13, through which it is drawn by the blower 14 which delivers it, as shown in Fig. 8, through one of the regenerating chambers 11 and thence by the passages 15 to the two hot air mains 16, from which it is distributed to the heating flues. Dampers 17, 18, 19, and 20, as seen in Fig. 8, are used to deflect the hot gases and the air respectively through the two regenerating chambers, so as to utilize the heat of the gases in heating the incoming air. All this will be well understood by those skilled in the art.

In accordance with my present improvements the combustion flues or heating flues in which the combustion takes place, are so arranged that very complete and uniform combustion occurs and a very even generation and distribution of heat throughout the side walls of each coking chamber occur. In the drawings, three reverted or U-shaped combustion flues 30 are arranged one above the other in each side wall of each oven and extending from the open end of the oven for approximately half its length, the other half of the oven being similarly provided with combustion flues extending in from the opposite end of the oven, as shown. Each of these reverted flues is provided with a separate burner or gas inlet 35 and hot air inlets 40 and the waste products produced in each are carried off to the waste gas main 10 without passing or interfering with the combustion occurring in the combustion flues 30 that lie above or below it. This is accomplished as follows: Each of the combustion flues 30 extends inwards and then downwards, being reverted and continuing outwards in the opposite direction toward the mouth of the oven. At its outer end 41 it turns and extends, as shown in Fig. 6, away from the oven wall and from the end of the oven to the vertical flue 42. This flue 42 is common to the three superposed flues 40 in the side wall of the oven and also to the three similar flues in the side wall of the adjacent oven, as shown. This vertical flue 42 leads the waste gases downwards and through the short connection 43 to the horizontal flue 44 which extends centrally under one of the ovens and at its inner end turns downwards into the down-take flue 45 that delivers to the waste main 10. It will be seen that each reverted or U-shaped combustion flue, therefore, has its

own air inlets 40 and gas inlet 35, and delivers its products of combustion to the waste gas main without passing the burner or air inlets of any of the other combustion flues or 5 in any way interfering with the combustion therin.

The gas is carried to the gas inlets 35 by a suitably located main 36 and branch pipes 37 leading downward, as at 38, to the three 10 perposed burners or gas inlets 35 beside the mouth of each oven. The air inlets 40 are supplied from the hot air mains 16. An uptake 31 from the main 16 is provided at each 15 end of each wall of each oven. At the level of each row of air inlets 40 the uptake 31 branches laterally, as at 32, and supplies a horizontal hot air flue 33 that leads directly to the openings or air inlets 40.

It will be seen that the mixing of gas from 20 the inlets 35 and air from the inlets 40 in each of the combustion flues, is independent of and is not interfered with by the waste products from any of the other combustion flues, and that each gas inlet and coöperating row 25 of air inlets has its separate and individual combustion flue from which the waste products are separately and independently drawn; and furthermore, that the conditions occurring in the uppermost flues are duplicated in 30 the lower combustion flues, thus producing very uniform generation and distribution of heat throughout the side walls of the ovens.

What I claim is:

1. An oven having in its side wall a plurality of separate combustion flues which are arranged one above the other, a downtime flue with which the said flues separately and individually communicate, gas inlets for the said combustion flues, hot air flues for the 40 same extending in the wall adjacent to the combustion flues and communications thereto from the respective combustion flues.

2. An oven having combustion flues within its side wall extending horizontally one 45 above another and a separate gas inlet for each, a hot air supply for each comprising a branching flue within the oven wall, there being one branch flue for each combustion flue extending adjacent thereto in the said 50 wall, and a downtime passage or flue for the waste gases to which the said combustion flues severally lead, whereby the waste gases from one flue do not affect the combustion in the others, and the heated air is delivered to 55 the combustion flues separately from the gas inlets.

3. In combination in an oven and in its side wall, a gas inlet, a combustion flue leading therefrom, a second gas inlet and combustion 60 flue beneath and parallel with the first, a waste gas passage for both the said flues communicating separately with each, and hot air flues and connections within the said wall for admitting hot air to the combustion 65 flues.

4. In combination with the oven, a plurality of combustion flues in its side wall arranged one above another, and a gas inlet, hot air inlets and waste gas outlet for each of the combustion flues separately, said hot air inlets entering the combustion flues at a plurality of points separate from the said gas inlet.

5. In combination with the oven, a plurality of combustion flues in its side wall arranged one above another, and a gas inlet, 75 hot air inlets and waste gas outlet for each of the combustion flues separately, a common hot air uptake branching within the said wall to supply the said flues, and a common downtime for the waste gases with which the outlets of the flues communicate.

6. In combination with the oven, a plurality of combustion flues in its side wall arranged one above another, and a gas inlet, 85 hot air inlets and waste gas outlet for each of the combustion flues separately, and a waste gas downtime into which the said outlets deliver and a hot air passage within the said wall having 90 branches extending to the respective combustion flues.

7. In combination in the side wall of an oven, two or more gas inlets one above the other, a plurality of reverted combustion flues extending horizontally one from each 95 one of the said gas inlets, a waste gas flue extending vertically and with which the said combustion flues severally communicate, and an air supply for the said flues including branch hot air flues within the said wall and 100 communicating with the combustion flues separately from the gas inlets.

8. In combination in the side wall of an oven, a plurality of heating flues one above another, two or more gas inlets therefor for 105 producing combustion at separate points, and a waste gas passage with which the flues from each gas inlet communicate individually and hot air flues within the said wall for the respective heating flues.

9. In combination in the side wall of an oven, a plurality of heating flues therein one above another, a plurality of gas inlets from which the heating flues severally and individually lead, air inlets therefor, and a waste 115 gas flue with which the said heating flues communicate, whereby the products of combustion of one flue do not mix with the incoming fresh air and gas of the adjacent flue for the purposes set forth said air inlets comprising hot air flues branching within the said wall and leading to the respective heating flues.

10. In combination in an oven and with its wall, a hot air uptake flue within the said 125 wall, a waste gas downtime flue within the said wall, a plurality of gas inlets and of combustion flues leading therefrom within the said wall and individually communicating with the said downtime, and hot air 130

branch flues from the said hot air uptake flue communicating with the said combustion flues.

11. In combination in an oven and with its
5 wall, a hot air uptake flue within the said
wall, a waste gas downtime flue within the
said wall, a plurality of gas inlets and of com-
bustion flues leading therefrom within the
said wall and individually communicating
10 with the said downtime and hot air branch

flues from the said hot air uptake flue extending parallel with the combustion flues and connected to supply hot air thereto.

In testimony whereof I have signed this specification in the presence of two subscr- 15
ing witnesses January 8th 1908.

MATHEW E. ROTHBERG.
